July 25, 1882

No. 13,082

UNITED STATES PATENT OFFICE.

JOHN GLEN, OF BROOKLYN, NEW YORK.

DESIGN FOR A PRINTED FABRIC.

SPECIFICATION forming part of Design No. 13,082, dated July 25, 1882.

Application filed May 18, 1882. Term of patent 3½ years.

To all whom it may concern:

Be it known that I, JOHN GLEN, of Brooklyn, in the county of Kings and State of New York, have invented a new and original Design for Printed Fabrics; and I do hereby declare that the following specification, taken in connection with the accompanying illustration, forming a part of the same, is a full, clear, and exact description thereof.

10 My design relates particularly to printed fabrics known as "calicoes," although it is equally applicable to silks, woolens, and other fabrics, either printed or woven.

15 It consists in the representation of birds in flight among the branches of trees or shrubs, as will hereinafter appear.

Referring to the illustration, A A' represent different views of birds in flight among branches B of a tree or shrub. As shown in the illustration, vines C, bearing flowers and leaves, and of a different color from the branches, are

combined therewith upon the ground of the fabric; but the vines may be omitted, if desired. The birds, branches, and vines are repeated upon the surface of the fabric to form 25 the pattern.

The fabric may be produced in any preferred variety or combination of colors for obtaining a desired effect.

What I claim, and desire to secure by Letters 30 Patent, is—

1. The design for printed or other fabrics, consisting of birds in flight among the branches of a tree or shrub, substantially as set forth.

2. The design for printed or other fabrics, 35 consisting of birds in flight among the branches of a tree or shrub, and flowering vines, substantially as described and shown.

JOHN GLEN.

Witnesses:

CHAS. G. TODD,

JOHN G. DATER.
